LOCOMOTIVE EXHAUST MECHANISM

Application filed October 12, 1926. Serial No. 141,081.

This invention relates to locomotive exhaust mechanism, and more particularly to exhaust nozzles. Its primary object is to provide efficient, rugged and reliable means for controlling or varying the locomotive exhaust at will to suit the varying conditions of operation of the engine.

Variable exhaust mechanisms, in the locomotive art, have not always proven practicable, primarily by reason of the fact that they have not been able to function properly under the severity of the conditions imposed upon them in service. Among such conditions may be mentioned: First, the high temperatures obtaining in the smoke box, the products of combustion passing therethrough varying from 500° to 600° F. and higher; second, the cinders passing from the flues at high velocity and often in substantial quantities; and third, the gumming and corrosion of parts resulting from the mixture of moisture from the steam with small particles of coal; not to mention the physical vibration and pounding incident to the intermittent exhaust impulses.

The device of the present invention is a variable exhaust nozzle so constructed as to meet these conditions, and overcome the disadvantages usually incident to variable exhaust mechanisms, and, in short, as previously stated, to provide efficient, rugged, and reliable means for varying the locomotive exhaust.

A further object of the invention is to embody, in such a mechanism, the advantages of easy adjustment and operation in service.

Still another object is to provide a mechanism to accomplish the foregoing which shall, at the same time, be simple of construction, and readily applicable to existing locomotives, with little or no alteration thereto.

How we obtain the foregoing, together with such other advantages as are incident to the invention, or may appear to those skilled in the art, will be clear from the following description, together with the accompanying drawings, in which:—

Fig. 1 is a somewhat diagrammatic fragmentary side elevational view of a locomo-

tive showing the application of our invention thereto;

Fig. 2 is a section on the line 2—2 of Fig. 1, with certain parts in elevation;

Fig. 3 is an enlarged top view of the variable nozzle shown in Figs. 1 and 2, half in plan and half in section;

Fig. 4 is a section taken on the line 4—4 of Fig. 3, illustrating the mounting and control of the movable elements or fingers of the nozzle;

Fig. 5 is a cross section of one of the fingers taken on the line 5—5 of Fig. 3; and

Fig. 6 is a similar cross section, on the line 6—6 of Fig. 3.

Referring first to Figs. 1 and 2, it will be seen that we have there illustrated a locomotive smoke box 2 having the usual stack 3, deflector plate 4, screen or netting 5, diaphragm plate 6, exhaust pipe 7, and other parts, of common construction. Mounted on the exhaust pipe 7, in the position of the usual exhaust nozzle, is the variable nozzle 8, of the present invention, the control lever 9 of which is movable from the cab of the engine by means of the lever 10 adjustable on the quadrant 11, the control being effected through suitable operating rigging, such as the rod 12, rocker arm 13, rocker shaft 14, arm 15, and rod 16. By reference particularly to Figs. 2 and 4, it will be seen that the nozzle is conveniently mounted on the top of the ordinary exhaust pipe by means of flanges 17 and 18 and bolts 19.

Referring now to Figs. 3 and 4, the variable nozzle, taken as a whole, includes a nozzle portion proper, 21, directing the exhaust blast upwardly, and a casing 20 forming an annular pocket or channel 25 for receiving the fingers 27 and their operating ring 26. The casing 20, as here shown, comprises a flange 23 attached to or integral with the nozzle 21, and a cover piece formed with an annular upper portion 22 and rim 24, this flange and upper cover being secured together by the bolts 30 and forming the peripheral internal channel or groove 25. In this circumferential, encased channel 25 is seated the operating ring 26, which is adapted to actuate a plurality of nozzle members or fingers 100

27, shutterwise, by engagement therewith through the medium of pins 28, each of which extends upwardly in a slot-like or elongated opening 29 in the respective finger 27. Each finger is pivotally mounted, for its shutterwise movement, on one of the pins or bolts 30 which extend through and clamp together the portions 22 and 23 of the enclosing casing. For the movement of the arm 9 actuating the operating ring, there is provided a slot 31 in the side of the device.

15 The fingers 27, as shown in cross section in Figs. 5 and 6, vary in contour from the base to the tip, being, however, generally wedge-shaped with the entering edge toward the exhaust blast. When constructed as shown, they will, when fully extended, as in Fig. 3, forms four substantially triangular nozzle-like exhaust passages 32. The contour 20 of the inclined faces 33, 34, may be such as to impart a helical motion to the exhaust, and may bear such an angular relation, the one to the other, as to minimize or neutralize any turning movement which might be set up in the finger by the force of the exhaust impulses, and, thus, to obviate the tendency of the exhaust to throw the nozzle out of adjustment.

30 It will now be clear that in the operation of the device the effective area of the nozzle opening may be varied over a considerable range by the extension or retraction of the fingers 27, without altering the effective overall dimensions or diameter of the blast passage (which, for efficient results, as is well known in this art, must bear a fixed predetermined relation to the dimensions and relative position of the smoke stack), and that said fingers will all be moved in unison 35 by the operating ring 26, through the medium of the arm 9 and the operating rigging connected to the lever 10 in the cab of the engine. It will also be obvious that the adjustment thereof may be done automatically, by any suitable means, such, for example, as disclosed in Patent No. 1,477,730, issued December 18, 1923, to A. J. Townsend and H. W. Snyder.

40 All the operating parts of the nozzle are protected from the soot, cinders, and direct heat of the smoke box by the enclosing annular cover with its channel 25, and even the tips of the nozzle fingers, when fully retracted, lie wholly within the said channel or recess. The position of the fingers, when fully retracted, is indicated in dotted lines at the left of Fig. 3. From the foregoing, it may be seen that our device is capable of a wide range of adjustment, is readily installed in existing motive power, is easy of operation, rugged in construction, and well protected from the deleterious effects of heat, gases and cinders in the smoke box.

45 It will be obvious that nozzles of oval, rectangular or other cross section might be em-

ployed, and that variations in the form and number of the nozzle fingers, the construction of the operating rigging, etc., might be made, without departing from the spirit and scope of our invention.

We claim:

1. Locomotive exhaust mechanism comprising a pocketed nozzle, casing with an exhaust passage therethrough, and members extending into said passage and retractable into said pocket, said members being spaced apart, circumferentially of the passage, so that in either extended or retracted position thereof the effective diameter of the exhaust jet through said passage remains the same.
2. An exhaust nozzle having fingers therein extensible into and retractable from the nozzle passage and spaced apart angularly therearound so that the effective diameter of the exhaust jet remains the same with the fingers in either position.
3. A locomotive exhaust nozzle comprising a casing having an annular recess and members, located at spaced intervals therearound, extending into the exhaust passage and retractable into said recess.
4. A locomotive exhaust nozzle comprising a casing having an annular recess and members extending into the exhaust passage and pivotally mounted for retraction into said recess.
5. A locomotive exhaust nozzle comprising a casing having an internal peripheral annular recess and members mounted therein and extendable into the exhaust passage, together with an operating ring adapted to move said members into and out of said passage.
6. A locomotive exhaust nozzle comprising a casing having an internal peripheral annular recess and members mounted therein and extendable into the exhaust passage, together with an operating ring adapted to move said members in unison into and out of said passage.
7. A locomotive exhaust nozzle comprising a casing having an annular recess and members extending into the exhaust passage and pivotally mounted for retraction into said recess, together with an operating ring and means connecting said ring and said members.
8. A locomotive exhaust nozzle comprising a casing having an annular recess and members extending into the exhaust passage and pivotally mounted for retraction into said recess, together with operating mechanism therefor also mounted in said recess.
9. In mechanism of the character described, a casing constructed with an exhaust passage therethrough, and an internal peripheral channel, fingers pivotally mounted in the channel each having an elongated opening therein, and an annulus seated in the channel and having members engaging said elongated

openings, said annulus being adapted when moved to swing said fingers horizontally on their pivots and extend them into said passage.

5 10. In mechanism of the character described, a casing constructed with an exhaust passage therethrough, and an internal peripheral channel, fingers pivotally mounted in the channel each having an elongated 10 opening therein, a rotatable annulus seated in the channel and having means of engagement with said elongated openings, and operating mechanism for the annulus.

11. In mechanism of the character described, a casing constructed with an exhaust passage therethrough, and an internal peripheral channel, fingers pivotally mounted in the channel each having an elongated 15 opening therein, a rotatable annulus seated 20 in the channel and having means of engagement with said elongated openings, and operating mechanism for the annulus, comprising an arm attached thereto and extending through the casing, and rigging extending 25 from thence to the cab of the locomotive.

12. In a variable exhaust nozzle, a retractable finger of substantially wedge cross-section, disposed with the entering edge of the wedge toward the stream of the exhaust line, 30 whereby the stream is divided when the finger is extended.

13. In a variable exhaust nozzle, a retractable finger of substantially wedge cross-section and varying in contour progressively 35 from its end disposed with the entering edge of the wedge toward the stream of the exhaust line, whereby the stream is divided when the finger is extended.

14. An exhaust nozzle having members of 40 wedge-shaped cross-section mounted for a diaphragm shutter movement into and out of the nozzle passage and each disposed to present an entering edge of the wedge to the stream of exhaust whereby the stream is divided when the members are in extended position.

15. An exhaust nozzle having pivoted members swingable horizontally into and out of the exhaust passage, the pivot points being spaced apart peripherally of the nozzle 50 at intervals wider than the width of said members.

16. Locomotive exhaust mechanism 55 formed with a blast passage of predetermined outside dimensions, and members mounted for extension into the line of said blast to alter its cross-sectional area, and so positioned with respect to the passage and to each other as to leave the effective outside 60 dimensions of the former substantially unaltered by extension of the members.

In testimony whereof we have hereunto signed our names.

WILLIAM E. WOODARD.
L. GEORGE TANDY.
